UNITED STATES PATENT OFFICE

2,494,616

ELECTRIC CAN OPENER

Fred Hensel, Los Angeles, Calif.

Application September 26, 1946, Serial No. 699,385

19 Claims. (Cl. 30—4)

1
This invention relates to an electric can opener, a device including an electrical driven cutter adapted to be reciprocated by an electric motor and capable of operative connection thereto at will, together with means for engaging and advancing the opener around the edge of a tin can to cause the blade of the cutter to effectively sever the top of the can adjacent the top bead thereof, and additional means whereby the severed top of the can may be lifted out and removed without the use of the fingers or a separate instrument for this purpose.

Another object of the invention is to provide a portable electric can opener, which is provided with a handle having means operatively connecting the driving motor contained within the housing of the opener, with a cutting knife which is normally operatively disconnected from the motor, and having means operated by the reciprocation of the cutting knife, to advance the opener around the beaded edge of the can so as to effectively sever the top thereof from the body of the can within the top bead of the latter.

Another object of the invention is to provide a compact portable electric can opener, in which all of the parts including the driving motor in operative connection with a cutting blade are housed within the device, which is relatively compact, strong, simple and effective in operation, and operable by one hand, leaving the other hand free to hold the can or for other purposes.

Other objects and advantages reside in the details of construction and operation as more fully hereinafter described and claimed, reference being had to the accompanying drawings forming part hereof, wherein like numerals refer to like parts throughout, and in which:

Figure 1 is a perspective view of an electric can opener constructed in accordance with the invention as applied to a can for opening the latter;

Figure 2 is an enlarged detail sectional elevation, showing the cutter in position and means for picking up the severed top of the can after the same is cut;

Figure 3 is a sectional elevation taken adjacent the handle of the device, showing the drive connections to the cutter blade;

Figure 4 is a view similar to Figure 3 of a fragmentary portion of the device, taken on the plane of the frame of the device at one side;

Figure 5 is a sectional elevation taken at right angles to Figure 3;

Figure 6 is a sectional view taken on the line 6—6 of Figure 7;

2

Figure 7 is a sectional elevation showing the manner of supporting the cutting blade;

Figure 8 is a sectional view taken at right angles to Figure 7;

Figure 9 is an enlarged sectional elevation showing the means for advancing the can opener around the rim of a can, and

Figure 10 is a perspective view of a clutch lever for the device.

Referring to the drawings in detail, in which like reference characters designate corresponding parts throughout the several views, the device is shown housed within a plastic or other housing 10 to which an extension cord 11 with the usual plug 15 for plugging into a wall socket, is provided at the top through an opening or gromet 12. The housing 10 is suitably mounted on a relatively rectangular open frame 13 the inturned bottom portions of which are spaced apart as shown. The top of the frame is provided with a central bearing 14, for the rotor shaft 15 of an electric motor 16 bolted thereon as indicated at 17 and through a top bearing member 18 disposed above the motor housing which is thereby supported on the frame 13. Fixed to the projecting lower end of the shaft 15, is a fly wheel 19 and a small beveled pinion 20, set screws being shown for this purpose.

Mounted between the sides of the frame, preferably stationarily, below the pinion 20, is a horizontal shaft 21 which may be suitably retained in position, as by a bracket or strip 22 secured to the side of the frame to engage one end of the shaft on which a larger beveled pinion 23 is rotatably mounted and meshes with the pinion or gear 20.

The beveled pinion or gear 23 is provided with a transverse opening 24 adjacent to its hub or sleeve bearing on the shaft 21. The gear or pinion 23 is thus loose on the shaft 21 and adjacent thereto and also loose on the shaft, is an eccentric collar or cam 25 having a transverse opening 26 aligned with the opening 24 engaged by a collar or band 27 formed at one end of a connecting rod 28 on the opposite end of which is mounted a spherical enlargement or ball 29, shown threaded or otherwise mounted on a shank 30 of the connecting rod.

A grooved clutch collar 31 is also loose on the shaft 21 and has a transverse hole or aperture 32 receiving a clutch pin 33 parallel to its axis, to extend into the hole 26 of the cam 25 and adapted to be forced into the opening 24 of the gear 23, in order to operatively connect the plunger or connecting rod 28 with the gear for reciprocation as the gear is driven from the motor. The pin 33 is provided with a beveled

lateral projection or lug 34 riding through a slot in the collar 31 at the outside and the pin is normally held inwardly by a spring 35 in the form of a ring anchored to one side of the collar 31 as indicated at 36 and tending to force the pin of the clutch in position to connect the cam 25 to the gear 23 at the will of the operator.

Normally, the pin is held disengaged from the gear 23 at the opening 24 and for this purpose a shift lever or clutch lever 37 is pivoted in a bearing bracket 38 at one side of the frame 13, as indicated at 39, the free end of the lever having a tapered camming surface or thickened portion 40 which is designed to engage in the groove of the collar 31 to normally force the pin 33 outwardly by engagement with the projection 34 operating in the slot of the collar but adapted upon being swung upwardly and out of the groove of the collar, in front of the projection 34, to permit the spring 35 to force the pin inwardly to engage the opening 24 of the gear 23, as a form of clutch connection normally disconnected and adapted to be clutched for connecting the connecting rod 28 to the gear 23 in order to rotate the collar 25 in the form of a cam as described, to rotate eccentrically and impart reciprocation to the connecting rod. A handle for supporting the instrument implement in one hand, is indicated at 41, and extends through an opening 42 in one side of the housing to be grasped as shown in Figure 1 of the drawings. The handle has a bifurcated inner end in the form of a fork with strap portions at the sides, as indicated at 43, for attachment to the sides of the frame 13 by screws or other suitable means and may be bolted or otherwise secured to the frame and housing as indicated at 44. The clutch lever 37 is pivoted at its outer end to the lower end of a plunger 45 which operates through a passage in the handle 41 adjacent the housing and has a button or finger piece 46 at the top for pressing the same downwardly to disengage the camming end of the lever from the groove of the collar. However, the plunger is normally held upwardly by a coil spring 47 resiliently held in a counter-bore 48 in the handle and pressing against the bottom of the button 46 so that when the plunger is pressed downwardly by the hand gripping the handle 41, the clutch is engaged by permitting the spring 35 to force the pin 33 into the opening 24 of the gear 23 and cause reciprocation of the connecting rod 28.

The ball terminal 29 of the connecting rod is held in a separable socket 49 at the upper end of a plunger 50, the socket including a spherical recess with a retaining plate 51 secured by screws or otherwise to the top of the socket to permit the shank to pass therethrough for slight angular motion. In addition to the ball and socket joint, connecting the plunger or ram 50 for reciprocation as the connecting rod is oscillated, the plunger or ram passes through a ball bearing 52 at the bottom of the frame and housing, the inner race of the ball bearing holding a ram guide or sleeve 53 and the race being held in position at its outer portion or ring, and clamped to the frame by means of bolts 54 in connection with a ring 55 similar to a washer, with an intermediate felt grease retainer or sealed ball bearing to take up lateral thrust on the ram or plunger 50 as the latter operates through a bottom opening in the frame 13.

The lower end of the plunger or ram 50 has a reduced portion 56 formed with a diametrical slot 57 adapted to take the reduced shank por-

tion 58 of a cutting blade 59 having an arcuate tapered cutting edge 60 at its lower end. The blade is held in position by a sleeve 61 engaged on the reduced portion 56 of the plunger or ram 50, which has a threaded socket engaged by a set screw 62 threaded through an aperture in the sleeve 61. The cutting blade or knife 59 has a notch 58' engaged by the screw 62 and edge of the knife 59 opposite the cutting edge 60 and is provided with a reduced portion forming an inclined offset 63 in the manner of a camming surface adapted to actuate a propelling or walking device in the form of a pusher to advance or move the can opener around the beaded top edge or rim of the can C, the rim bead of which is designated at R and the top of which is designated at T, being the part to be severed and removed for opening the can. As shown in Figure 1 of the drawings, the can may be supported upon a table or other support and held by the other hand while one hand grasps the handle 41, to support and operate the can opener in position to connect and disconnect the cutter at will by merely pressing the button 46 and releasing pressure therefrom.

Secured upon diametrically opposite sides of the guide sleeve 53, are plates or feet 64 fastened jointly by screws 65 with an angular yoke 66 having spaced sides or legs extending horizontally for connection thereto outwardly of the feet or plates 64 at the top due to the bifurcated character of the yoke or bracket. The bottom of the guide sleeve or housing 53 abuts a bracket plate 67 anchored as at 68 to one side of one plate 64 and slotted as at 69 to receive the blade 59 therethrough. The yoke 66 has its lower end curved inwardly as at 70 and is connected to form a bight portion having a sleeve 71 in which a needle 72 is held by a set screw 73 to point upwardly and inwardly for engaging beneath the bead or rim R of the can, so as to hold the device down while cutting. An adjustment screw 74 is provided through the yoke 66 constituting the needle holder, to engage the back of a plate 64 having an extension 75 and adjust the position of the needle to properly engage beneath the bead of the can at its rim, on the screws 65 as a pivot. Incidentally, a spacing collar 21', may be provided on the shaft 21, between one side of the frame 13 and the clutch collar 31, to hold the latter and the eccentric or cam 25 against the gear 23, to prevent sidewise motion of said parts or movement thereof away from the gear 23.

The lower ends of the shoes or plates 64 are provided with notches 76 to receive the bead or rim of the can to guide and ride the device on the edge of the can. Inasmuch as the blade 59 is secured to the plunger or ram 50 and engages through the slot 56 of the guide plate 67, the plunger is held from turning in the guide 53. It should also be noted that one plate 64 extends angularly outwardly at its lower end and a U-shaped bracket 77 is fastened at one side to the plate 64 with extension 75 at its out-turned foot 65 portions, as indicated at 78, extending forwardly at right angles to the feet or plates 64 as more particularly shown in Figure 3 of the drawings. The outer or bight connecting portion thereof supports a leaf spring 79 attached by screws or the like as indicated at 80 and having its lower end curved inwardly in ogee or reversed fashion. A U-shaped pusher element 81 is provided at its sides with longitudinal or elongated slots 82 by which the same is pivotally mounted for longitudinal movement on a cross-pin 83 held between

the sides of the bracket 77 and normally urged downwardly by resilient means or spring 84 disposed between the bottom of the bracket and pin. The lower end of the pusher has a right angularly inwardly and upwardly extending tongue or arm in the form of a lug 85 extending through a slot 86 in the adjacent plate 64 to engage the camming surface or edge 63 of the knife blade 59 as the latter reciprocates up and down, to push the member 81 with an oscillating motion outwardly and upwardly on its cotter pin 83 against the action of the spring 84 which then exerts downward pressure to move the pusher downwardly. The base of the member 81 has a transverse slot 87 in which a hardened square edged small steel plate 88 is held by a set screw 89 threaded through the forward portion thereof to move forwardly on the beaded rim or edge of the can with the member or bracket 81 as the knife moves downwardly and is returned by the springs 79 and 84 in a downward direction rearwardly to engage the bead at the top edge of the can at which it rides and digs into the same under the pressure of the spring 84 to advance, propel or push and move the device forwardly about one-eighth inch every time the knife comes down so as to step the same along the can for additional cutting each time the knife goes up. The tubular knife guide or sleeve 53 for the plunger or ram 50 is designed to turn at the bearing 52 to follow the curvature of the can and the yoke or fork 66 which is pivoted at 65, may swing outwardly to permit the device to be applied so that the pin 72 will engage under the bead and is held in such engagement with the yoke 66 inwardly, by a coil spring 90 fastened to the bracket 77 and one leg or arm of the yoke 66 as shown in Figure 5 of the drawings, to cause the pin to press under the bead and hold the pusher down against the can. The knife 59 merely turns with the guide or sleeve 53 that is held from turning with respect thereto. Upon release of the clutch lever or button 46, the clutch and drive parts while still rotating, are disengaged so that the ram or plunger 50 always stops at the top position so as not to interfere at the knife, when the device is removed from the can since the knife is in a raised position as shown in Figure 9. It may also be mentioned that the housing 10 may be made in two sections so as to be readily applied or removed, with only the cutting mechanism disposed at the bottom below the housing together with the revolving ram guide or sleeve 53 with its attached needle holder, pusher and proper holes for the handle, ram guide and cable containing the wires for conducting the current from the socket of a house wire. The projecting portion 75 on one of the plates 64 has a permanent magnet shown as a horseshoe magnet 91 secured thereto as indicated at 92 to project from the upwardly inclined bottom edge of the plate portion 75, so that when the implement is tilted in the manner shown in Figure 2 of the drawings, after severing the top of the can, and the latter drops down upon the contents, the magnet will attract and pick up the disc top T in the tilted position of the device to remove the cutout top or lid which can be easily removed from the magnet and discarded. Also, the pivoted yoke 66 will swing on the screws 65 as a pivot against the resilient action of the spring 90 to back the needle 72 away from the can outwardly of the bead R, at the rim of the can, as also shown in Figure 2 so that the device can be raised and removed from the can. In this way, the can top is effectively cut to open the can and the severed top or lid easily removed

in a simple operation. Also, the pusher plate 88 is simply a small steel plate about one-quarter inch square, which moves up and down, the slots 82 allowing a one-quarter inch up and down movement of the plate and all eight edges of the plate may be used by changing its position through the medium of the set screw 89. It should be noted that the knife cuts very close to the inner corner of the lid or top of the can adjacent to the bead or rim R.

In the operation of the device, the can is set on the table or other horizontal supporting surface and held with the left hand while the opener is held in the right hand or vice versa and after the device is plugged into the wall socket at the end of the cable 11, to connect the motor 16, the device is applied to the can so that the arms of the yoke or fork 66 will swing outwardly to engage the needle 72 under the outside of the beaded rim R and the pusher plate 88 will engage on top of the edge or the can or rim. The clutch being normally disengaged, the motor will drive the large gear 23 while the pin 33 is retracted from the opening 24 thereof due to the clutch lever 37 being held upwardly at its outer arm or end by the spring 47 to raise the button 46 and the camming end of the lever 37 downwardly in the groove of the collar 31 to push outwardly on the pin 33 at its lug 34 against the spring 35. Therefore, by pressing the button 46 downwardly with a thumb or finger, the camming end of the lever at 40 is raised from the groove of the collar 31 to permit the spring 35 to force the pin 33 into the opening 24 and connect the latter to the eccentric or cam 25 for rotating the latter or causing vertical reciprocation of the connecting rod 28 and plunger or ram 50 at the universal joint connection of the latter with the connecting rod and thereby reciprocate the knife up and down. As the knife is operated, the pusher is oscillated or moved forward and then rearwardly under the action of the inclined camming surface 63 on the knife blade 59 and the spring 84 respectively, to move the device along the can as the knife blade cuts into the latter adjacent the rim of the can top. This is continued around the can until the top is entirely severed, and then the device is tilted as previously explained and in the manner shown in Figure 2 of the drawings, so that the magnet will remove the can lid or top T which has been severed. This is facilitated due to the knife being raised when the clutch is released so as not to interfere with the removal of the device from the can. This is effected by merely releasing the pressure on the button 46.

While in the foregoing there has been shown and described the preferred embodiment of this invention it is to be understood that minor changes in the details of construction, combination and arrangement of parts may be resorted to without departing from the spirit and scope of the invention as claimed.

What I claim as my invention is:

1. In a can opener a knife blade mounted to be advanced and retracted along its longitudinal axis, manually controlled means connected to the knife blade alternately to advance and retract the knife blade along said axis and means adjacent and actuated in unison with said knife blade to engage a can to be cut and advance said blade along a path which lies in a plane perpendicular to said longitudinal axis.
2. In a can opener a knife blade mounted to be advanced and retracted along its longitudinal

mounted adjacent and actuated upon the advance of the knife blade along said axis to engage a can to be cut and advance the blade along a path which lies in a plane perpendicular to said axis and means supported adjacent one side of the blade to engage the can to be cut and hold the can opener against movement away from the can during the advance of the blade along its longitudinal axis.

16. In a power driven can opener a guide, a knife blade mounted in said guide to be advanced and retracted through one end thereof along its longitudinal axis, a pair of spaced parallel feet extending longitudinally from the guide adjacent opposite edges of the knife blade, said feet having aligned can head receiving notches in their ends remote from the guide, manually controlled means connected to the knife blade alternately to advance and retract the knife blade along its longitudinal axis between the feet and means carried by the guide and actuated in unison with the movements of the knife blade to engage the can head and advance the knife blade along a path which lies in a plane perpendicular to its longitudinal axis.

17. In a power driven can opener a guide, a knife blade mounted in said guide to be advanced and retracted through one end thereof along its longitudinal axis, a pair of spaced parallel feet extending longitudinally from the guide adjacent opposite edges of the knife blade, said feet having aligned can head receiving notches in their ends remote from the guide, manually controlled means connected to the knife blade alternately to advance and retract the knife blade along its longitudinal axis between the feet and means carried by the guide and actuated in unison with the advance of the knife blade along its longitudinal axis to engage the can head and advance the knife blade along a path which lies in a plane perpendicular to the longitudinal axis of the knife.

18. In a power driven can opener a guide, a knife blade mounted in said guide to be advanced and retracted through one end thereof along its longitudinal axis, a pair of spaced parallel feet extending longitudinally from the guide adjacent opposite edges of the knife blade, said feet having aligned can head receiving notches in their ends remote from the guide, manually controlled means connected to the knife blade alternately to advance and retract the knife blade along its longitudinal axis between the feet and means carried by the guide and actuated by the knife blade to engage the can head and advance the knife blade along a path which lies in a plane perpendicular to the longitudinal axis of the knife blade.

19. In a power driven can opener a guide, a knife blade mounted in said guide to be advanced and retracted through one end thereof along its longitudinal axis, a pair of spaced parallel feet extending longitudinally from the guide adjacent opposite edges of the knife blade, said feet having aligned can head receiving notches in their ends remote from the guide, manually controlled means connected to the knife blade alternately to advance and retract the knife blade along its longitudinal axis between the feet and means carried by the guide and actuated by the knife blade during its advance along its longitudinal axis to engage the can head and advance the knife blade along a path which lies in a plane perpendicular to the longitudinal axis of the knife.
